ALKYLATION OF PHENOLS

Charles G. Dryer, Chicago, Ill., assignor to Universal Oil Products Company, Chicago, Ill., a corporation of Delaware

No Drawing. Application April 28, 1938,
Serial No. 204,905

3 Claims. (Cl. 260—624)

The object of this invention is a process of alkylating phenols.

In the art of inhibiting the deterioration of unstable gasolines and other substances as developed at the present time the compounds of outstanding merit are principally of a phenolic or an amino-phenolic character although in some instances amines and other compounds have sufficiently high inhibiting value. As many of the pure compounds are expensive and difficult to prepare, recourse is frequently had to the use of crude phenolic liquors which are produced from the distillation of hydrocarbon materials such as wood, coal and lignite, and also to the crude tar acids separable therefrom by treatment with alkalis and later acidification. Since the effectiveness of these semi-refined products is dependent primarily upon the effectiveness of the phenolic compounds which they contain and since these inhibitors are diluted with hydrocarbon and other compounds of a relatively inert character, it is necessary in practice to employ only those fractions which contain inhibiting compounds of outstanding potency as otherwise the amount of crude tar which needs to be added will be so great that the color of gasolines or other compounds to which they are added may be adversely affected. In extreme cases undesirable odors may be imparted.

While few fixed and invariable rules have been evolved as to the relation between structure and inhibiting effectiveness even in the case of definite groups of compounds such as phenols and amino-phenols mentioned, there are few exceptions to the rule that the addition of alkyl groups to the ring hydrogens tends generally to increase oil solubility and decrease water solubility and reactivity with alkalis. The present invention is a contribution to the art of improving the inhibiting value of crude phenol-containing products.

In one specific embodiment the present invention comprises treatment of crude phenol-containing tars to improve the inhibiting value thereof by subjecting said tars to treatment with olefinic hydrocarbons in the presence of catalysts consisting of sulfuric acid containing boric acid.

I have determined that the phenolic compounds in crude tars may be alkylated by olefins in the presence of relatively concentrated sulfuric acid which contains a relatively small amount of boric acid without experiencing the adverse effects observed when boric acid is absent. When strong sulfuric acid is employed as an alkylation catalyst it is commonly observed that there are side

reactions involving polymerization and condensation reactions involving unsaturated hydrocarbons and other compounds which result in the formation of heavy dark-colored tarry and resinous materials which are more or less insoluble in hydrocarbons and which impart color or cloudiness to gasolines even when the tars are used in small amounts of the order of 0.1%. When, however, a minor percentage of boric acid is added to sulfuric acid of approximately 96% concentration to produce an alkylating catalyst mixture, these side-reactions are minimized and alkylation proceeds as the principal reaction so that the phenolic compounds can be improved in their inhibiting characteristics without rendering the total tar inapplicable to the treatment of gasoline.

The process of treating the crude tars with olefins in the presence of the preferred catalysts involves only relatively simple operations. A tar fraction is mixed with approximately 15% by weight of concentrated sulfuric acid containing about 10% of boric acid at slightly elevated temperatures of the order of 120° F. and olefins are gradually added until the desired degree of alkylation is effected. As a rule it is not necessary to use olefins of higher molecular weight than octenes and sufficiently good improvements in inhibiting potency are obtainable by utilizing the olefin-containing gas fractions produced in the cracking of petroleum as will be shown in later examples, these gas mixtures being introduced into the well-stirred mixture of acid catalyst and tar until the desired degree of alkylation has been accomplished.

In treating crude phenol-containing tars according to the process of the present invention one effective method of contacting which may be applied to continuous operation consists in forcibly injecting normally gaseous olefins or olefin-containing vapors, acid catalyst and tar into mixing devices positioned inside the top of filled columns, the emulsion produced being allowed to trickle downwardly over the filling material to complete the initiated reactions, all reaction products being withdrawn from the bottom of the tower and separated into a lower liquid layer comprising partially spent acid catalyst, an upper liquid layer comprising the treated tar fraction and any residual fixed gases. In case the olefinic content of gas separated at this point is still high enough for further reaction, the gases may be recycled. Furthermore, the acid layer may be continuously re-used until its effectiveness drops below a practical minimum. The treated tar may be then subjected to distillation to produce separate frac-

tions of varying inhibiting value, using vacuum as a general rule to prevent thermal decomposition reactions.

On account of the complex character of the reactions which must necessarily be involved when tars of complex composition are treated, it is impossible to follow the exact course of the reactions which take place and there may be other effects than those due to alkylation of both phenols and other inhibiting substances such as, for example, phenolic ethers; however, beneficial effects have been uniformly observed in the inhibiting effectiveness of various tars and reliance is placed upon the observed results rather than any specific reaction which may occur.

It should be apparent to those familiar with inhibitors and the principles of organic chemistry that the exact effects of treating different crude tars with different olefins or olefin-containing mixtures in the presence of catalysts are not exactly predictable on account of the complex character of the tars and the number of olefins which may be employed for the alkylation of their inhibiting constituents. It is therefore not to be presumed that the effects of treating various tars by the present process are uniform or exactly predictable since some will respond better to treatment than others. As will be shown in later examples, fractions which are too low in inhibiting value to be used are frequently improved sufficiently so that their use is practical and in other cases there is only a slight improvement which is not sufficient to warrant the practical application of the process. It is presumed that preliminary tests will be conducted upon different tars to which the process may be applied to determine whether they are capable of sufficient improvement to warrant the application of the process.

The following examples are given to indicate 40 the value of the invention in connection with the treatment of various tars although as already stated, the invention is of broad scope and the examples are not introduced with the intent of imposing specific limitations thereon.

Example I

A fraction of a lignite tar boiling within the range of 185-230° C. was intimately mixed with 15% by weight of 96% sulfuric acid containing 10% of boric acid and the mixture was maintained at a temperature of 120° F. while a butane-butylene fraction produced in the fractionation of a cracked gas mixture was introduced until

there was a gain of 55% in weight. The process was then stopped and the acid layer separated from the oily products which were then washed with water and sodium carbonate and mildly heated under vacuum to remove water. The final yield of distilled tar was 137% of the original.

The original and the treated tar fraction were each used to treat a gasoline produced by cracking a paraffinic oil, this gasoline showing an induction period in the oxygen bomb test of 145 minutes. The addition of the 0.01% of the original lignite tar distillate raised the induction period to 205 minutes. The use of the same quantity of alkylated product raised the induction period to 275 minutes. It will thus be seen that there was not only a gain in weight of inhibiting fraction but also that the inhibiting value was also raised. Multiplying the percentage increase in weight by the increase in inhibiting potency gives a factor of 2.9 which may be designated as the "inhibitor quotient."

Example II

In this case a fraction of lignite tar boiling from 200 to 300° C. was treated in the presence of the same catalyst with a butane-butylene fraction to a 53% gain in weight. After separation of the acid catalyst, washing and distillation, it was found that the yield of inhibitor was 140%. In this instance the inhibiting value as measured by the increase in induction period in the oxygen bomb was the same as the original and the value of the treatment was evident by the increase in yield.

In both of the preceding examples the solubility of the fraction in gasoline was markedly increased and the resistance to removal by accidental water or aqueous alkali contact was found to be reduced.

I claim as my invention:

1. A process for alkylating phenols which comprises reacting the same with an olefin in the presence of sulfuric acid containing a small amount of boric acid.
2. A process for alkylating phenols which comprises reacting the same with an olefin in the presence of concentrated sulfuric acid containing about 10% by weight of boric acid.
3. A process for alkylating phenols which comprises reacting the same with a normally gaseous olefin in the presence of sulfuric acid containing a small amount of boric acid.

CHARLES G. DRYER.
